CLAIM

The ornamental design for a liquid level sender assembly, as shown and described.

DESCRIPTION

FIG. 1 is a perspective view of our liquid level sender assembly;

FIG. 2 is a front view thereof;

FIG. 3 is a right side view thereof;

FIG. 4 is a back view thereof;

FIG. 5 is a left side view thereof;

FIG. 6 is a top view thereof; and,

FIG. 7 is a bottom view thereof.

The broken line showing of the environment in FIG. 1 is for illustrative purposes only and forms no part of the claimed design.
